(57) **CLAIM**

The ornamental design for a suspension coupler, as shown and described.

DESCRIPTION

FIG. 1 is a perspective view of a suspension coupler showing the new design;

FIG. 2 is a right-side elevation view thereof;

FIG. 3 is a left-side elevation view thereof;

FIG. 4 is a front elevation view thereof;

FIG. 5 is a back elevation thereof;

FIG. 6 is a top plan view thereof;

FIG. 7 is a bottom plan view thereof;

FIG. 8 is a first exploded view thereof;

FIG. 9 is a second exploded view thereof; and,

FIG. 10 is a second perspective view, showing an alternative mounting plate in dashed lines.

The broken lines depicting mounting brackets, mounting plates, and attachment hardware are for the purpose of illustrating the unclaimed portions of the article and form no part of the claimed design.
